UNITED STATES PATENT OFFICE.

WILLIAM A. NADVORNIK, OF DETROIT, MICHIGAN.

MEANS FOR REMOVABLY SUPPORTING MOP-WRINKING MECHANISMS.

1,360,309.

Specification of Letters Patent. Patented Nov. 30, 1920.

Application filed September 5, 1919. Serial No. 321,832.

To all whom it may concern:

Be it known that I, WILLIAM A. NADVORNIK, a citizen of the United States of America, residing at Detroit, in the county 5 of Wayne and State of Michigan, have invented certain new and useful Improvements in Means for Removably Supporting Mop-Wrinking Mechanisms, of which the following is a specification, reference being had 10 therein to the accompanying drawings.

This invention relates to improvements in means for removably supporting mop-wrinking mechanisms.

Mop-wringers generally include movable 15 elements located above the liquid contents of the pail and means located external of the pail for moving these elements into and out of wringing position, such external means being operated by a foot of the operator 20 whose hands are engaged in manipulating the mop. Owing to the fact that wringing the mop practically requires that it be drawn upwardly through the wringing means in order that the liquid wrung from the mop 25 may return to the pail contents, it is essential that the mechanism be held against upward movement during the upward-drawing of the mop, and to provide this result it is the general practice to fixedly secure the 30 mechanism to the pail itself in order to prevent relative movement of pail and mechanism during this operation.

These facts have resulted in the use generally of wooden-containers or pails for the 35 liquid, permitting a more ready securing of the pail and mechanism together as well as providing a more substantial connection than is made possible by attempting to rivet the mechanism to a sheet metal container, 40 the rough conditions of service tending to break down such connections.

The present invention is designed to provide an arrangement by which the wringing mechanism and pail are firmly held in 45 proper relation during the wringing operation, but in such manner as to prevent the practice of dragging the pail by the mop. This is obtained by practically retaining the pail and mechanism as independent elements 50 with no direct and positive connection between them but with the wringer structure so formed that the pail forms a support for the structure during operation. As a result, any attempt at dragging the pail over the 55 floor will result in separating the pail from

the mechanism and generally upset the pail, the arrangement being such, however, as will permit the pail and mechanism to be shifted if the operator raises them bodily by the pail handle and carries the combination to the 60 new point. Obviously, the necessity for raising the pail takes it out of contact with the floor and thus eliminates the wear on the pail heretofore caused by the dragging operation. This enables the use of sheet metal 65 pails, if desired, and practically limits the life of the pail only by the deteriorating action of the liquid content. And since the entire mechanism is bodily removable with no material difficulty, the pail itself can be 70 readily cleansed and kept clean, the entire interior being exposed by removal of the mechanism.

To these and other ends, therefore, the 75 nature of which will be readily understood as the invention is hereinafter disclosed, said invention consists in the improved construction and combination of parts, hereinafter more fully described, illustrated in the accompanying drawings, and more particularly pointed out in the appended claims.

In the accompanying drawings, in which similar reference characters indicate similar parts in each of the views,—

Figure 1 is a perspective view showing 85 one way in which the present invention may be carried out, the wringing mechanism shown being one commonly employed commercially.

Fig. 2 is a vertical sectional view taken 90 through the removable structure, the pail being shown in dotted lines, the parts being shown in position for active service.

Fig. 3 is a top plan view of the removable portion shown in Fig. 1, the pail being illustrated in dotted lines.

Fig. 4 is a view in elevation.

In the drawings A indicates generally the structure of a well-known form of mop-wrinking mechanism, the structure employing a frame α^* in which is fixedly positioned a pair of rolls α and a movable roll α' , the latter being moved toward and from rolls α by the operation of a foot member or lever α^2 through the operation of a number of 105 connections arranged to translate the up and down pivotal movements of lever α^2 external of the pail, into horizontal reciprocating movements of roll α' internal of the pail above the liquid content of the latter; in 110

some cases the connections are such that downward movement of the lever straightens out a toggle connection in such manner as to automatically lock the parts in closed position, but it is generally required that the operator produce the pressure by retaining his foot upon the lever, this additionally acting to retain the pail on the floor during the upward movement of the mop.

10 In the commercial form heretofore employed, frame a^x is generally secured to the inner face of the pail, lever a^2 being carried by a suitable support secured externally of the pail, the operating connections extending 15 over the top of the pail wall.

15 In the drawings, the pail is indicated at B and, for the present invention carries the usual handle or bail b , the pail being of the usual commercial type usable for any desired purpose.

20 The changes made will now be described. 10 indicates a supporting member for the internal portion of the wringing mechanism, this member being preferably band-like and may be a complete approximately-circular formation or of segmental form, the latter being illustrated, frame a^x being secured to this member by suitable means as by riveting. As seen in the drawings, 25 this member 10 when in position lies adjacent the inner periphery at the top of the pail, and may act in the nature of a centering or positioning structure for the mechanism to retain the latter from shifting freely 30 about within the pail.

35 11 indicates a supporting member external of the pail and to which the lever a^2 and its support are secured, as shown, member 11 being plate-like in form and preferably having a vertical length extending 40 from adjacent the top to the bottom or adjacent the bottom of the pail, the member being curved somewhat transversely of such length. As shown in Fig. 2, member 11 need 45 not closely fit the exterior face of the pail and may be of any preferred configuration, that shown having a relatively wide top and narrow bottom, the top width permitting the connections 12 between members 10 and 50 11 to be spaced apart a material distance—preferably sufficient to reduce liability of rocking of the internal portion of the mechanism within the pail in use. Connections 55 12 may—as shown in the drawings—be formed integral with member 11 and be bolted or otherwise secured to member 10; obviously, connections 12 may be in the form of separate straps with the outer ends secured to member 11, this being an obvious change. Where connections 12 are integral with member 11, member 10 need not 60 extend throughout the complete circular form, member 11 completing the annular formation to prevent member 10 from tend-

ing to spring or be distorted during opera- 65 tion.

13 designates a movable member having arms 13^a the free ends of which are pivotally connected to strap members 14 secured to member 10 opposite connections 12, members 70 14 projecting outwardly over the top of the pail so as to locate the pivot points external of the pail.

75 In operative position, member 13 extends downwardly, practically into contact with the floor, forming a member on which the operator can place one foot while depressing lever a^2 at the other side of the pail—members 14 may or may not contact with the top of the pail. With member 13 held in 80 this position and lever a^2 depressed the wringing mechanism will be firmly anchored in such way as not to place any pressures on the pail in directions tending to disturb its position, thus permitting the usual mop-wringing operation as at present.

85 Should, however, it be desired to shift the pail from one position to another, it will be necessary to grasp handle b and raise the pail—and the wringing mechanism in position thereon—from the floor, since the pail is not of sufficient vertical length to permit its being dragged, with the operator walking upright and a stooping position is uncomfortable—especially in the presence of the weight of the mechanism. To attempt to grip the mop in position and drag the combination simply results in moving the mechanism upward within the pail to a point where its further movement laterally 95 will upset the pail, there being no actual connection between the mechanism and the body of the pail.

90 To remove the mechanism bodily it is necessary only to raise member 13 to the horizontal—as in dotted lines in Fig. 1—thus permitting the internal mechanism to be raised to clear the top of the pail, the mechanism then being moved laterally to carry member 13 beneath handle b , leaving 100 the pail entirely free of the mechanism. This operation is reversed when the mechanism is to be restored.

105 The parts are so arranged that small variations may be had in size, etc., of pail 110 without affecting the ability to employ the mechanism with it.

115 Obviously, the general principles of the invention are not limited to use in connection with the specific type of mop-wringing 120 mechanism shown. And while I have shown and described one way in which the invention may be carried out, it will be readily understood that changes and modifications therein may be found desirable or be required in meeting the various exigencies of use, and I desire to be understood as reserving the right to make any and all such 125

changes or modifications therein as may be found desirable or essential in so far as the same may fall within the spirit and scope of the invention as expressed in the accompanying claims, when broadly construed.

Having thus described my invention, what I claim as new is:

1. As a means for removably supporting a mop-wringing mechanism in operative position relative to a pail, supporting means at one side and external of the pail, supporting and holding means external of and positionable at the opposite side of the pail, and connections between said several means and the 10 mop-wringing mechanism internal of the pail for positioning the latter above the liquid content of the pail, said several means being free from securing engagement with the pail.
2. Means as in claim 1 characterized in that the supporting and holding means is pivotally mounted to permit shifting between a 15 position in juxtaposition to the floor and a position to permit movement beneath the 20 bail of the pail.
3. As a means for removably supporting a mop-wringing mechanism in operative position relative to a pail, and wherein the mechanism includes mop wringing members 25 positionable above the liquid content of the pail and means located external of the pail for moving the wringing members into and out of wringing position, a support for the external means positionable external of the 30 pail and having a fixed connection with the frame of the internal portion of the mechanism, and a member positionable external of the pail in spaced relation to said support and also having connection with said internal portion of the mechanism, said member, 35

in operative position, being held by the foot of the operator to maintain the mechanism in position during the wringing activity of the mechanism, said several means being free from securing engagement with the pail.

45

4. Means as in claim 3 characterized in that the holding member is pivotally mounted to permit shifting from such operative position to a position to permit removal with the internal portion of the mechanism from 50 beneath the pail bail.

5. Means as in claim 3 characterized in that the support and member are connected internal of the pail by a member forming a support for the internal portion of the mechanism and which is of a configuration to position said mechanism portion against material lateral shifting.

55

6. The combination with a pail having a bail, of a mop-wringing unit positionable 60 relative to the pail to permit mop-wringing action therein, said unit including means external of and located on opposite sides of the pail for maintaining the position of the wringing mechanism during wringing operation, said means including an element shiftable between positions above and below the top plane of the pail, the means at one side being operative to maintain the wringing rolls in wringing position, said mechanism 65 unit being bodily removable from the pail by element manipulation, said unit being unsecured to the pail.

70

In testimony whereof I affix my signature in the presence of two witnesses.

WILLIAM A. NADVORNIK.
